his Attorney.

UNITED STATES PATENT OFFICE.

JAMES E. SEELEY, OF LOS ANGELES, CALIFORNIA; ADA R. SEELEY ADMINISTRATRIX
OF SAID JAMES E. SEELEY, DECEASED.

METHOD FOR MAKING LEAD PIGMENT.

1,325,960.

Specification of Letters Patent.

Patented Dec. 23, 1919.

Application filed February 5, 1917, Serial No. 146,645. Renewed October 6, 1919. Serial No. 328,931.

To all whom it may concern:

Be it known that I, JAMES E. SEELEY, a citizen of the United States, residing at Los Angeles, in the county of Los Angeles and 5 State of California, have invented a new and useful Method for Making Lead Pigment, of which the following is a specification.

This invention relates to a production of 10 lead pigment, and the main object of the invention is to provide for making such pigment of a white color and of high quality at a minimum of expense.

The making of white lead by the ordinary 15 process now in use is a slow and expensive operation. Attempts have been made to produce white lead in a more rapid and economical manner by the direct action of air and water on the lead aided by mechanical agitation. As heretofore produced 20 however, such a process has not produced a satisfactory quality of white lead, for the reason that the product was generally grayish or discolored, whereas the trade requires 25 a pure white article.

An important object of the present invention is to provide for the production of a lead pigment which is pure white and is of extreme fineness and suitable quality for 30 use as a pigment.

My process consists essentially in subjecting lead while agitated in the presence of the water to the action of ozonized air in such manner that the oxidization of the 35 lead is greatly accelerated as compared with ordinary air oxidation. In order to promote oxidation, it is desirable to reduce the lead to a state of fairly fine subdivision, and my invention further includes, as a 40 step in the process, a special mode of operation for producing such subdivision. My invention also preferably comprises supplying carbon dioxid along with the ozonized air, so as to improve the quality of the prod- 45 uct.

The accompanying drawings illustrate apparatus suitable for carrying out my invention and referring thereto:

Figure 1 is a vertical section of the apparatus 50 for converting the finely divided metallic lead into lead pigment.

Fig. 2 is a vertical section of the apparatus for reducing the metallic lead to a finely divided condition.

55 The apparatus shown in Fig. 1 comprises

an ozonizer 1, a plurality of reaction cells or tanks 2, 3, 4, settling tanks 5 and 6 and suitable pipe connections for conducting the ozonized air to said cells and for conducting the liquid as hereinafter set forth. 60

The ozonizer 1 may be of any suitable construction, comprising, for example a tube 7 of insulating material, provided with inlet and outlet means 8 and 9 for passing air therethrough, with an internal electrode 10 extending axially in said tube and with an external electrode 11 surrounding said tube, said electrodes 10 and 11 being connected by wires 12 and 13 to the high tension winding to a step-up transformer 70

14, whose low tension winding is connected to an alternating supply circuit indicated at 17 and 18. The outlet pipe 9 for the ozonizer leads to a pump or blower 20, having an outlet pipe 21 connected by branch pipes 22, 23, and 24, provided with valves 26, 27, and 28, to the lower ends of the respective cells 2, 3 and 4. Each of these cells may consist of a vertical tubular receptacle 75

or tank, which may be open at its upper end for escape of air therefrom. An over-flow pipe 30 leads from the upper part of cell 2 to the lower part of cell 3, and an over-flow pipe 31 leads from the upper part 80

of cell 3 to the lower part of cell 4. An over-flow pipe 33 leads from the upper part 85

of cell 4 to branch pipes 34 and 35, having valves 36 and 37, which discharge into settling tanks 5 and 6 respectively. Said settling tanks are provided with pipes 38 and 39 having valves 40 and 41 respectively for drawing off the settled material from said tanks. Decanting pipes 42 and 43 extend from the tanks 5 and 6 respectively to the pipe 44 leading to the pump 45 whose outlet pipe discharges through a valve 46 into a reservoir or tank 47. Said reservoir has an outlet 48 provided with a valve 49 and discharging into the first reaction cell or 90

tank 2. 100

The apparatus for reducing the lead to finely divided condition may be constructed as shown in Fig. 2, comprising for example, a melting pot 50 adapted to be heated by a suitable furnace 51 and having an outlet pipe 52, provided with a valve 53 and adapted to discharge the liquid lead into a body of water or other liquid in tank 54. Said tank may be provided with suitable means for supplying liquid thereto and with 110

means 55 for drawing liquid therefrom when required.

In order to reduce the lead to finely divided condition, it is placed in pot 50 and 5 melted and allowed to run through pipe 52 in a fine stream into the body of liquid in tank 54 and the resulting violent expansion produced by the contact of the melted lead with the liquid, causes mechanical breaking 10 up of the lead into fine particles, which are well adapted for the reactions required in my process.

The finely divided lead is discharged into the first reaction cell 2 and enough water 15 is supplied to said tank to fill the same up to the level of the overflow pipe 30. When the process is well under way, all of the cells 2, 3 and 4 will be filled up to the level of their overflow pipes and water will be con- 20 tinually furnished from the reservoir 47 to maintain a continual overflow from each cell to the next and from the last cell to the settling tank 5 or 6, which for the time being is connected through its valve 25 36 or 37 to the pipe 33, the other settling tank being at that time cut off from such connection. Atmospheric air is drawn con- tinually through inlet 8, ozonizer 1 and out- 30 let 9 and forced through valves 26, 27 and 35 28 into the lower parts of the respective reaction cells 2, 3 and 4. Such air being ozonized in passing through the ozonizer and producing in each cell an upward current of air bubbles, in which the air is ozon- 35 ized sufficiently to produce a strong oxidiz- ing effect. The velocity of this upward air current is also sufficient to produce a con- siderable agitating action. Thus in the first 40 reaction cell 2 finely divided lead is sub- jected to rapid oxidation by agitation there- of in the presence of ozonized air and water. The current of atmospheric air thus caused to pass through the body of water in contact with the finely divided lead, contains also 45 a small proportion of carbon dioxid, so that the finely divided lead is subjected to carbonizing action as well as oxidation, with the result that finely divided lead pigment consisting wholly or partially of white lead 50 is formed and rises to the upper part of the body of water in the cell 2 and overflows with the water through pipe 30 into the cell 3. If desired, an additional amount of carbon dioxid may be supplied to the air for 55 increasing the carbonating action. The body of finely divided lead in cell 2 is preferably maintained at a sufficient distance below the overflow pipe 30 to prevent any particles of unaltered lead from being carried over with 60 the white lead and water through pipe 30. The material passing off through pipe 30

into reaction cell 3 will, in general, be some- what grayish in color, said material being subjected in reaction cell 3 to further oxidation by the ozonized air supplied through pipe 23, with the result that it overflows through pipe 31 in a much lighter or whiter condition. This operation may be repeated as often as necessary to produce a pure white product. The final product overflows 70 through pipe 23 to the settling tank 5 or 6 and is collected therein by settling. Said tanks are alternately cut off from the supply pipe so as to facilitate settling out of the white lead. The clear overlying liquid 75 may then be drawn off through the pipe 42 or 43 by pump 45 and forced into reservoir 47 from which it flows through the valve 49 to the reaction cell 2.

What I claim is:

1. The process of making a lead pigment, which consists in subjecting finely divided lead to agitation in the presence of water and ozonized air.

2. The process of making a lead pigment 85 which consists in passing a current of ozonized atmospheric air upwardly through a body of divided lead immersed in water, in such manner that the ozonized air oxidizes and agitates the lead and carries the result- 90 ing finely divided lead compound upwardly out of the body of divided lead.

3. The process of making a pigment con- 95 taining white lead which consists in subject- ing lead to the action of ozone, in the pres- ence of water and carbon dioxid.

4. The process of making a pigment con- 100 taining white lead, which consists in subject- ing lead to the action of atmospheric air containing ozone and carbon dioxid, in the presence of water.

5. The process of making lead pigment, which consists in agitating a body of di- 105 vided lead in the presence of water and ozonized air in such a manner as to produce a lead compound, removing such compound from said body of divided lead and subject- ing said compound to further action of ozonized air in the presence of water.

6. The process of making a pigment con- 110 taining white lead which consists in melting lead, passing a fine stream of such melted lead into water to produce finely divided lead having a coating of oxid, and subject- ing such divided lead to the action of ozon- 115 ized air, in the presence of water and car- bon dioxid.

In testimony whereof I have hereunto set my hand, at Los Angeles, California, this 24th day of January, 1917.

JAMES E. SEELEY.
